RAILWAY SIGNAL LIGHTING CONTROL
APPARATUSOtto W. Rost, Chicago, Ill., assignor to The Union
Switch and Signal Company, Swissvale, Pa., a
corporation of Pennsylvania

Application March 2, 1949, Serial No. 79,167

10 Claims. (Cl. 246—46)

1

My invention relates to railway signal lighting control apparatus, and particularly to apparatus for at times effecting the lighting of a lamp for a railway signal which is normally unlighted.

It is common practice, in the railway signaling art, to control an approach lighting relay for a given signal in series with a control relay or winding for the next signal in the rear which governs traffic movements in the same direction as the given signal, as shown, for example, in Letters Patent of the United States No. 1,790,524, granted January 27, 1931, to Lester E. Spray for Railway Signaling Systems.

In some instances, however, the circuit for energizing a control relay or winding for the next signal in the rear, which governs traffic movements in the same direction as the given signal, may not be suitable for controlling an approach lighting relay for the given signal. In such instances, in order to save the material and labor necessary to provide a separate control circuit for the approach lighting relay for the given signal, it may be possible to control the approach lighting relay for the given signal over a control circuit for the next opposing signal in advance of the given signal.

One feature of my invention is the provision of an arrangement, embodying manually controllable means, for at times controlling a lighting control relay for a given signal in series with a control element such, for example, as a relay or other winding for the next opposing signal in advance, and for at other times controlling the same lighting control relay by only that portion of the control circuit for the next opposing signal in advance which is controlled by traffic conditions in the rear of the given signal. It follows that the lighting control relay, in apparatus embodying my invention, at times serves to effect the lighting of a given signal when the control circuit for the next opposing signal is deenergized although it is manually controlled to be energized, and that the lighting control relay serves at other times as only an approach lighting relay.

With apparatus embodying my invention, one advantage is that, when a train is moving in the direction in which a given signal governs traffic movements, the lamp of the given signal is extinguished as soon as the train has completely passed the signal and has theretofore left the approach track section in the rear of the given signal. Needless lighting of the given signal after a train has passed the given signal, moving in the direction in which the given signal governs traffic movements, is thereby prevented.

2

Another advantage, in apparatus embodying my invention, is that the lighting of a given signal may show that a train is approaching the given signal in either direction.

5 I shall describe two forms of apparatus embodying my invention, and shall then point out the novel features thereof in claims.

In the accompanying drawings, Figs. 1a and 1b, when placed end to end, with Fig. 1a at the 10 left, constitute a diagrammatic view showing one form of apparatus embodying my invention, in which a two-winding lighting control relay for a given signal is arranged so that at times only one of its windings is energized in series with control means for the next opposing signal in advance, and at other times both windings of the lighting control relay are energized by only a portion of the control circuit for the next opposing signal in advance; and Fig. 2 is a diagrammatic 15 view showing a modified form of the apparatus of Figs. 1a and 1b in which a one-winding lighting control relay for the given signal is arranged so that at times it is energized in series with control means for the next opposing signal in advance, and at other times it is energized, in series 20 with a resistor, by only a portion of the control circuit for the next opposing signal in advance. 25

Similar reference characters refer to similar parts in each of the views.

30 Referring first to Figs. 1a and 1b, a stretch of railway track is shown divided by insulated joints 5 into track sections 3T, 4RT, 1T, and 2LAT, over which traffic movements may be made in both directions. In order to simplify the drawings, the 35 stretch of track, although comprising two parallel series of track rails, is represented by a single line. Section 1T is connected with an auxiliary track by a track switch 1, and section 3T is connected with an auxiliary track by a track switch 3.

40 Each of the track sections is provided with a track circuit including a suitable source of current such, for example, as a battery & connected across the rails adjacent one end of the section, and a track relay, designated by the reference character R with a distinguishing prefix 45 which is the same as the reference character for the associated track section, connected across the rails adjacent the opposite end of the section.

50 Signals, designated by the reference characters 2R and 4R, govern traffic movements toward the right, as shown in the drawings, which I shall assume is the eastbound direction. Signals 2L and 4L govern traffic movements in the opposite or 55 westbound direction. The signals may be of any

suitable design such, for example, as the well-known semaphore or the searchlight type. Each of the signals may be provided with lighting means such, for example, as lamp 4LE shown for a given signal 4L.

Each of the signals is controlled by a polarized home control relay, designated by the reference character HSR with a prefix which is the same as the reference character for the associated signal. Signal 2L, for example, is controlled by relay 2LHSR, and signal 2R is controlled by relay 2RHSR. Relays 2LHSR and 2RHSR are shown controlled by a manually operable signal lever 2V which has a normal position *n*, a reverse position *f* to the left, and a reverse position *r* to the right, as shown in the drawings. Relays 2LHSR and 2RHSR are shown controlled by lever 2V through direct wires, but may be of a polar stick type controlled from a remote point through any suitable medium such, for example, as the time code apparatus shown and described in Letters Patent of the United States No. 2,273,383, granted February 17, 1942, to Clarence S. Snavely and Alfred B. Miller, for Remote Control Systems. Signals 4L and 4R are controlled by relays 4LHSR and 4RHSR, respectively, which are controlled by a lever 4V similarly to the manner in which relays 2LHSR and 2RHSR are controlled by lever 2V.

Each of the signals is operated, by a circuit controlled by a reverse contact of the associated home control relay, for displaying a proceed indication. The reverse contact of each home control relay is normally open, and becomes closed when the associated signal lever is moved to a corresponding reverse control position *f* or *r*. Contact 23 of relay 2LHSR, for example, becomes closed when lever 2V is moved to the *f* position, and contact 8 of relay 2RHSR becomes closed when lever 2V is moved to the *r* position. Each of the signals is therefore normally conditioned to display the stop indication.

Stop indication repeater relays, designated by the reference characters 2LRPR and 4LRPR, are controlled in conjunction with signals 2L and 4L, respectively. Each of these relays is energized by a circuit including a contact 9 of the associated signal which is closed when and only when the associated signal is displaying a stop indication.

A proceed indication repeater relay 2RGPR is controlled in conjunction with signal 2R, and is energized through a contact 33 of signal 2R which is closed when and only when signal 2R is displaying a proceed indication.

Approach locking stick relays, designated by the reference characters 2LSR and 4LSR are associated with signals 2L and 4L, respectively. Time element devices, designated by the reference characters 2LTE and 4LTE, which may be of the thermal type, are associated with relays 2LSR and 4LSR, respectively.

Signal 4R, which is the next opposing signal in advance of the given signal 4L, is provided with a control element or winding which is shown as a polarized signal control relay 4HDR. This relay is controlled by a reverse polar contact of the home control relay 4RHSR, by track relays 1TR, 3TR, and 4RTR, by approach locking relays 2LSR and 4LSR, and by pole-changing contacts of relay 2RGPR. Relays 2LSR, 1TR, and 4RTR are responsive to traffic conditions on the stretch of track in the rear of the given signal 4L, and relays 4LSR and 3TR are responsive to traffic conditions on the stretch of track between signals 4L and 4R.

A contact 29, which is operated in conjunction with switch 3, is also included in the circuit for relay 4HDR. This contact is closed when switch 3 is in the normal position, as shown, and becomes opened when switch 3 is moved to its reverse position.

Lamp 4LE of signal 4L is controlled by a lighting control relay designated by the reference character 4LER. This relay is controlled, either by a reverse polar contact of relay 4RHSR in series with relay 4HDR, or by a normal polar contact of relay 4RHSR and by a portion only of the control circuit for relay 4HDR controlled by traffic conditions in the rear of signal 4L.

In the modified form of apparatus shown in Fig. 2, the lighting control relay 4LER has only one control winding instead of two windings as shown in Fig. 1a. The winding of relay 4LER, in the form of apparatus shown in Fig. 2, is controlled in series with relay 4HDR through a reverse contact of relay 4RHSR, and is connected by a normal contact of relay 4RHSR through a resistor *t* with a portion only of the control circuit for relay 4HDR which is controlled by traffic conditions in the rear of signal 4L.

Having described, in general, the arrangement and control of the various parts of apparatus embodying my invention, I shall now describe the circuits and operation in detail.

As shown in the drawings, all parts of the apparatus are in the normal condition, that is, all track sections are unoccupied, and therefore track relays 3TR, 4RTR, 1TR, and 2LATR are energized; each of the switches 1 and 3 is in the normal position for a train movement along the stretch of main track; each of the levers 2V and 4V is in its normal or *n* position, and therefore the lower winding, as shown in the drawings, of each of the relays 2LHSR, 2RHSR, 4LHSR, and 4RHSR is energized; each of the signals 2L, 2R, 4L, and 4R is displaying the stop indication; each of the relays 2LRPR, 4LRPR, 2LSR, and 4LSR is energized; both windings of relay 4LER, as shown in Fig. 1a, are energized, and the one winding of relay 4LER shown in Fig. 2 is energized; and relays 2RGPR and 4HDR, and time element devices 2LTE and 4LTE are deenergized.

As shown in Figs. 1a and 1b, the lower winding of each of the relays 2LHSR, 2RHSR, 4LHSR, and 4RHSR is controlled by a circuit which includes a normal contact of the associated control lever closed in the normal position. The lower winding of relay 4LHSR, for example, is controlled by a circuit which includes contact 1 of lever 4V closed in the *n* position. The lower winding of relay 4RHSR is similarly controlled by a circuit which includes contact 8 of lever 4V closed in the *n* position.

Relay 4LRPR is energized by a circuit passing from terminal B of a suitable source of current, through contact 9 of signal 4L, and the winding of relay 4LRPR to terminal N of the same source of current. Relay 2LRPR is energized by a similar circuit.

Both a pickup and a stick circuit are closed for energizing relay 4LSR. The pickup circuit for this relay passes from terminal B, through contact 10 of relay 4LHSR, contact 11 of relay 4LRPR, contact 12 of relay 4RTR, and the winding of relay 4LSR to terminal N. The stick circuit for relay 4LSR is the same as the pickup circuit just traced except that it includes the front point of contact 13 of relay 4LSR instead of contact 12 of relay 4RTR. Relay 2LSR is also energized by pickup and stick circuits which

are similar to the pickup and stick circuits just traced for relay 4LSR.

Relay 4LER, as shown in Figs. 1a and 1b, is energized by a circuit which includes a portion only of the control circuit for relay 4HDR, which is controlled by traffic conditions in the rear of signal 4L. This circuit passes from terminal B, through contact 14 or relay 2LSR, contact 15 of relay 1TR, back point of contact 16 or relay 2RGFR, conductor 34, the lower winding 17 of relay 4LER, contact 18 of relay 4RHSR closed in the normal or left-hand position, upper winding 19 of relay 4LER, contact 20 of relay 4RTR, and the back point of contact 21 of relay 2RGPR to terminal N. The circuit for relay 4LER, in the form of apparatus shown in Fig. 2, is the same as the circuit just traced except that it includes the winding of relay 4LER instead of the upper winding 19 only of relay 4LER shown in Fig. 1a, and includes a resistor t instead of the lower winding 17 of relay 4LER shown in Fig. 1a.

I shall assume that, with apparatus arranged as shown in the drawings, a westbound train enters section 2LAT, deenergizing relay 2LATR. Contact 12 of relay 2LATR then opens the pickup circuit described for relay 2LSR which, however, remains energized by its stick circuit previously described.

I shall assume further that the dispatcher or leverman moves lever 2V to the *f* position for clearing signal 2L. The upper winding of relay 2LHSR will therefore be energized by a circuit controlled by contact 7 of lever 2V closed in the *f* position. Contact 16 of relay 2LHSR will therefore open the pickup and stick circuits for relay 2LSR, causing relay 2LSR to become deenergized.

Contact 14 of relay 2LSR will therefore open the circuit previously traced for relay 4LER, causing relay 4LER to become deenergized. With relay 4LER deenergized, lamp 4LE of signal 4L will be lighted by a circuit passing from terminal BX of a suitable source of lighting current, through contact 22 of relay 4LER, and lamp 4LE to terminal NX of the same source of lighting current.

With the upper winding of relay 2LHSR energized, contact 23 of this relay will become closed, and therefore signal 2L will be operated to its proceed position by a circuit passing from terminal B, through contact 23 of relay 2LHSR, and the mechanism of signal 2L to terminal N. The arm of signal 2L, upon being moved away from its stop position, opens its contact 9, thereby deenergizing relay 2LRPR which opens its contact 11 in the pickup and stick circuits previously described for relay 2LSR which are, however, already open at contact 16 of relay 2LHSR.

If, now, the leverman should desire to stop the train at signal 2L, he will return lever 2V to its *n* position, thereby opening the circuit for the upper winding of relay 2LHSR and causing the lower winding of relay 2LHSR to again become energized because contact 7 of lever 2V is again closed in its *n* position. Contact 23 of relay 2LHSR will therefore now again be opened and contact 16 will now again be closed. With contact 23 of relay 2LHSR opened, the operating circuit for signal 2L will be opened, and therefore the arm of signal 2L will return to the stop position. Relay 2LRPR will therefore again be energized by its circuit previously traced.

With relay 2LATR deenergized because of a train on section 2LAT, the pickup circuit previously described for relay 2LSR will now be open

at contact 12 of relay 2LATR, and therefore a circuit will be completed for energizing the time element device 2LTE. This circuit passes from terminal B, through contact 18 of relay 2LHSR, contact 11 of relay 2LRPR, back point of contact 13 of relay 2LSR, and time element device 2LTE to terminal N. Upon the lapse of a measured period of time, time element device 2LTE will close its contact 24, thereby completing a second pickup circuit for relay 2LSR, which is the same as the pickup circuit previously described, except that it includes contact 24 of time element device 2LTE instead of contact 12 of relay 2LATR.

With relay 2LSR again energized, relay 4LER will again be energized by the circuit previously traced. The circuit for lamp 4LE will therefore be opened at contact 22 of relay 4LER, causing lamp 4LE to be extinguished.

If, however, instead of stopping the train at signal 2L, the leverman permits it to proceed, then when the train enters section 1T, relay 1TR will become deenergized. Relay 1TR, upon becoming deenergized, opens its contact 15 in the circuit previously traced for relay 4LER. If the leverman then returns lever 2V to its *n* position, signal 2L will again be returned to its stop position, as previously described, and therefore relay 2LRPR will again be energized. With relay 1TR deenergized, a third pickup circuit will now be closed for relay 2LSR which is the same as the first pickup circuit described for this relay except that it includes contact 25 of relay 1TR instead of contact 12 of relay 2LATR.

With relay 2LSR energized, its contact 14 in the circuit for relay 4LER will now be closed, but with contact 15 of relay 1TR in this circuit now open, relay 4LER will remain deenergized. When the train enters section 4RT, relay 4RTR will become deenergized, and therefore its contact 29 will open the circuit for relay 4LER at still another point.

When the leverman clears signal 4L by moving lever 4V to its *f* position, relay 4LSR will become deenergized similarly to the manner in which relay 2LSR becomes deenergized when the leverman clears signal 2L, as previously described. Contact 27 of relay 4LSR will therefore now be opened, but this will not affect relay 4LER because contact 18 of relay 4RHSR is now closed in the normal position. Similarly, when the train enters section 3T, deenergizing relay 3TR and contact 28 of relay 3TR then opens, relay 4LER will not be affected, because contact 19 of relay 4RHSR is closed in the normal position.

When the train leaves section 4RT, permitting relay 4RTR to again become energized, the circuit previously traced for relay 4LER will again be closed, and therefore relay 4LER will be energized and extinguish lamp 4LE for signal 4L.

I shall now assume that, after the westbound train has passed over the stretch of main track shown in the drawings, and all parts of the apparatus are again in the normal condition, the leverman moves lever 4V to its *r* position to clear signal 4R for an eastbound train. If, however, for any reason, relay 4LSR should be deenergized at this time, relay 4HDR will not become energized, because contact 27 of relay 4LSR would be open, and relay 4LER will become deenergized because contact 18 of relay 4RHSR is now in the reverse position and therefore the circuit previously traced for relay 4LER is open.

If, however, relay 4LSR is energized, and if relay 3TR is energized, then the closing of con-

tact 18 of relay 4RHSR in its reverse position will complete a circuit for energizing relay 4LER in series with relay 4HDR, this circuit passing from terminal B, through contact 14 of relay 2LSR, contact 15 of relay 4TR, back point of contact 16 of relay 2RGPR, conductor 34, winding of relay 4HDR, contact 26 of relay 4LHSR, contact 27 of relay 4LSR, contact 28 of relay 3TR, contact 29 of switch 3, contact 18 of relay 4RHSR closed in the reverse or right-hand position, upper winding 19 of relay 4LER, contact 20 of relay 4RTR, and the back point of contact 21 of relay 2RGPR to terminal N. With relay 4LER thus energized, its contact 22 will remain open, and therefore lamp 4LE will remain unlighted.

With relay 4HDR energized by current of reverse polarity, signal 4R will be operated to a caution position by a circuit passing from terminal B, through contact 30 of relay 4HDR, contact 31 of relay 4HDR closed in the reverse or right-hand position, and the mechanism of signal 4R to terminal N.

If the leverman should clear signal 2R by moving lever 2V to its *r* position and thereby effecting energization of the upper winding of relay 2RHSR through contact 8 of lever 2V in the *r* position, relay 2RGPR would become energized when signal 2R is operated to the proceed position. The circuit for relay 2RGPR passes from terminal B, through contact 33 of signal 2R, and the winding of relay 2RGPR to terminal N. Relay 4HDR would then become energized by current of normal polarity in a circuit which is the same as the circuit previously traced for this relay except that it includes the front points of contacts 16 and 21 of relay 2RGPR instead of the back points of these contacts. Signal 4R would then be operated to a proceed position by its circuit passing from terminal B, through contact 30 of relay 4HDR, contact 31 of relay 4HDR in its normal or left-hand position, and the mechanism of signal 4R to terminal N.

When the eastbound train enters section 3T, deenergizing relay 3TR, contact 28 of relay 3TR will open the circuit traced for relays 4LER and 4HDR, causing these relays to be deenergized. With relay 4HDR deenergized, the operating circuits previously traced for relay 4R will be opened, causing signal 4R to again indicate stop. With relay 4LER deenergized, lamp 4LE will again be lighted by its circuit previously traced. It follows that, although the upper winding of relay 4RHSR is energized, causing its contact 18 to be closed in the reverse or right-hand position, lamp 4LE will now be lighted because of the traffic conditions between signals 4L and 4R, even though the traffic conditions in the rear of signal 4L are not at this time such as to cause lamp 4LE to be lighted.

When the train enters section 4RT, the circuit for relays 4LER and 4HDR will be opened by contact 20 of relay 4RTR at another point, so that these relays will remain deenergized and lamp 4LE will remain lighted. Similarly, lamp 4LE will remain lighted while the train moves through section 1T, causing contact 15 of relay 1TR to be opened.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. A lighting control arrangement for a given signal which is controlled to govern traffic movements in a given direction over a given stretch of railway track which is also provided with an opposing signal located in advance of said given signal for governing traffic movements in the opposite direction over said given stretch of railway track, in which a control winding for said opposing signal is controlled by a circuit which is controlled by traffic conditions in the rear of said given signal and also by traffic conditions between said given signal and said opposing signal, comprising, in combination, a lighting control relay for said given signal, manually operable means for selectively connecting said lighting control relay in said circuit in series with said control winding or connecting said lighting control relay in only the portion of said circuit which is controlled by traffic conditions in the rear of said given signal and which does not include said control winding, and a lighting circuit for said given signal controlled by said lighting control relay.

2. A lighting control arrangement for a given signal which is controlled to govern traffic movements in a given direction over a given stretch of railway track which is also provided with an opposing signal located in advance of said given signal for governing traffic movements in the opposite direction over said given stretch of railway track, in which a control winding for said opposing signal is provided with a control circuit which is controlled by manually controllable means and by traffic conditions in the rear of said given signal and also by traffic conditions between said given signal and said opposing signal, comprising, in combination, a lighting control relay for said given signal, means controlled by said manually controllable means for selectively controlling said lighting control relay by all of said control circuit for said opposing signal or by only the portion of said control circuit which is controlled by traffic conditions in the rear of said given signal, and a lighting circuit for said given signal controlled by said lighting control relay.

3. A lighting control arrangement for a given signal which is controlled to govern traffic movements in a given direction over a given stretch of railway track which is also provided with an opposing signal located in advance of said given signal for governing traffic movements in the opposite direction over said given stretch of railway track, in which a control winding for said opposing signal is provided with a control circuit which is controlled by traffic conditions in the rear of said given signal and also by traffic conditions between said given signal and said opposing signal, comprising, in combination, lighting control means for said given signal, manually controllable means for selectively controlling said lighting control means in series with said control winding in said control circuit or by only the portion of said control circuit which is controlled by traffic conditions in the rear of said given signal, and lighting means for said given signal controlled by said lighting control means.

4. A lighting control arrangement for a given signal which is controlled to govern traffic movements in a given direction over a given stretch of railway track which is also provided with an opposing signal located in advance of said given signal for governing traffic movements in the

opposite direction over said given stretch of railway track, in which said opposing signal is controlled by traffic conditions in the rear of said given signal and also by traffic conditions between said given signal and said opposing signal, comprising, in combination, lighting control means for said given signal, manually controllable means for at times controlling said lighting control means in series with said opposing signal and for at other times controlling said lighting control means by only traffic conditions in the rear of said given signal, and lighting means for said given signal controlled by said lighting control means.

5. A lighting control arrangement for a given signal which is controlled to govern traffic movements in a given direction over a given stretch of railway track which is also provided with an opposing signal located in advance of said given signal for governing traffic movements in the opposite direction over said given stretch of railway track, in which said opposing signal is controlled by traffic conditions in the rear of said given signal and also by traffic conditions between said signals, comprising, in combination, manually controllable means for at times lighting said given signal in response to traffic conditions in the rear of said given signal and for at other times lighting said given signal in response to said traffic conditions between said signals.

6. A lighting control arrangement for a given signal which is controlled to govern traffic movements in a given direction over a given stretch of railway track which is also provided with an opposing signal located in advance of said given signal for governing traffic movements in the opposite direction over said given stretch of railway track, in which a signal control circuit for said opposing signal is controlled by traffic conditions in the rear of said given signal and also by other conditions and by manually controllable means, comprising, in combination, a lighting control relay for said given signal included in said signal control circuit when said manually controllable means is conditioned for controlling said opposing signal to display a proceed indication but included in an approach lighting control circuit which includes only a portion of said signal control circuit which is controlled by traffic conditions in the rear of said given signal when said manually controllable means is conditioned to control said opposing signal to indicate stop, and a lighting circuit for said given signal controlled by said lighting control relay.

7. In combination, a stretch of railway track, a given signal for governing traffic movements in a given direction over said stretch of track, an opposing signal in advance of said given signal for governing traffic movements in the opposite direction over said stretch of track, a control element for said opposing signal, a manually controllable device having a normal and a reverse position, a lighting control relay for said given signal having two control windings, a circuit controlled by traffic conditions in the rear of said given signal and controlled by said manually controllable device in the normal position for energizing the two windings of said lighting control relay in series with each other, a second circuit controlled by traffic conditions in the rear of said given signal and also controlled by other conditions and controlled by said manually controllable device in the reverse position for energizing one of the windings of said lighting control relay in series with said control element for said op-

posing signal, and lighting means for said given signal controlled by said lighting control relay.

8. In combination, a stretch of railway track, a given signal for governing traffic movements in a given direction over said stretch of track, an opposing signal in advance of said given signal for governing traffic movements in the opposite direction over said stretch of track, a control element for said opposing signal, a manually controllable device having a normal and a reverse position, a lighting control relay for said given signal, a circuit controlled by traffic conditions in the rear of said given signal and also by traffic conditions between said signals and controlled by said manually controllable device in the reverse position for energizing said lighting control relay in series with said control element, a resistor, a second circuit including the portion of said first circuit which is controlled by traffic conditions in the rear of said given signal and controlled by said manually controllable device in the normal position for energizing said lighting control relay in series with said resistor, and lighting means for said given signal controlled by said lighting control relay.

9. In combination, a stretch of railway track, a given signal for governing traffic movements in a given direction over said stretch of track, an opposing signal in advance of said given signal for governing traffic movements in the opposite direction over said stretch of track, manually controllable means having a normal and a reverse position, a lighting control relay for said given signal, a control circuit for controlling said opposing signal in series with said lighting control relay controlled by said manually controllable means in said reverse position and controlled by traffic conditions in the rear of said given signal and also controlled by traffic conditions on said stretch of track between said signals, a second control circuit controlled by said manually controllable means in said normal position including only the portion of said first control circuit which is controlled by traffic conditions in the rear of said given signal for energizing said lighting control relay, and lighting means for said given signal controlled by said lighting control relay to be lighted when a train is approaching said given signal while said opposing signal is manually controlled to indicate stop and to be lighted when said opposing signal is manually controlled to display a proceed indication but is controlled by traffic conditions to indicate stop.

10. In combination, a stretch of railway track, a given signal for governing traffic movements in a given direction over said stretch of track, an opposing signal in advance of said given signal for governing traffic movements in the opposite direction over said stretch of track, a lighting control relay for said given signal, signal control means for said opposing signal, and manually controllable means for at times controlling said lighting control relay in series with said signal control means through means responsive to traffic conditions in the rear of said given signal and through means responsive to traffic conditions between said signals and for at other times controlling only said lighting control relay through means responsive only to traffic conditions in the rear of said given signal, and lighting means for said given signal controlled by said lighting control relay.
